E. W. ROBINSON.
BARREL HEAD RETAINER.
APPLICATION FILED DEC. 10, 1912.

1,104,546.

Patented July 21, 1914.

UNITED STATES PATENT OFFICE.

EDWARD W. ROBINSON, OF SAVANNAH, GEORGIA, ASSIGNOR TO INTERNATIONAL BARREL COMPANY, OF SAVANNAH, GEORGIA, A CORPORATION OF GEORGIA.

BARREL-HEAD RETAINER.

1,104,546.

Specification of Letters Patent. Patented July 21, 1914.

Application filed December 10, 1912. Serial No. 735,984.

To all whom it may concern:

Be it known that I, EDWARD W. ROBINSON, a citizen of the United States, residing in Savannah, Georgia, have invented certain 5 Improvements in Barrel-Head Retainers, of which the following is a specification.

The object of my invention is to provide a retainer for the heads of barrels, especially barrels of that type in which the staves are 10 interwoven with pairs of wires twisted together between the staves. This object I attain in the manner hereinafter set forth, reference being had to the accompanying drawing, in which—

15 Figure 1 is a sectional perspective view of part of a barrel and barrel head with retainer for the latter constructed in accordance with my invention; Figs. 2 and 3 are, respectively, perspective views of parts of 20 the different members of the retainer separated from one another; Fig. 4 is a similar perspective view illustrating the preliminary stage in the operation of uniting the members of the retainer, and Fig. 5 is a similar 25 perspective view illustrating the final stage in the operation.

In Figs. 2, 3, 4 and 5 the members of the retainer are shown in the straight position which they occupy before the retainer is bent 0 into the hoop form which it assumes before being applied to the barrel.

In Fig. 1 of the drawing, 1—1 represent certain of the staves of the barrel and 2—2 certain of the sections of the head of the 5 same. The staves are interwoven with pairs of wires 3, 3* which are twisted together between successive staves so as to retain the latter in proper relation to one another to form the desired bilged barrel, as set forth in my application for patent filed November 9, 1910, Serial No. 591,505.

The end pair of wires is located some little distance inwardly from the ends of the staves and the inner wire 3 of said end pair provides a support for the barrel head, the peripheral portion of the inner face of said barrel head bearing upon the wire 3, as shown in Fig. 1. The hoop or retainer for the barrel head is of inverted U shape in cross section so as to fit snugly over the ends of the staves and it is composed of an outer member 4 lying against the outer faces of the staves and an inner member 5 lying against the inner faces of the same, said in-

ner member having at its lower edge an in- 55 turned flange 6 which bears upon the outer face of the peripheral portion of the head and serves to confine the same firmly to its seat upon the inner wire 3 of the end pair, as shown in Fig. 1.

The outer member 4 of the retainer has a semi-circular bead 7 formed thereon, which bead engages with the outer wire 3* of the end pair, as shown in Fig. 1, and downwardly beyond said bead 7 the outer member 60 of the retainer has an outwardly flaring flange 8 so as to facilitate the slipping of the inner portion of the outer member 4 of the retainer over the wire 3* when the retainer is pressed onto the ends of the staves. 65

The two members of the retainer are united by means of an interlock joint at the outer corner of said retainer, which joint is formed in the following manner: Both members of the retainer are originally straight, 70 the inner member 5 of the retainer having at the top an outwardly projecting portion 75 9 of a width equal to the thickness of the staves, this portion constituting the top of the completed retainer and having, at its 80 outer edge, an upstanding flange 10. The outer member 4 of the retainer has at the top a downturned flange 11 which is first fitted over the upturned flange 10 of the inner member, as shown in Fig. 4, the engaging 85 flanges being then bent down over the top 9 of the retainer, as shown in Fig. 5. The straight members of the retainer when thus locked together are then bent into hoop form and the meeting ends are united by welding 90 or any other available means, so as to permanently maintain the retainer in the hoop form.

As the outer portion of the horizontal top 9 of the retainer is, when the latter is bent 95 into hoop form, of greater diameter than the inner portion, I provide for the necessary expansion of such outer portion by forming slits 12 at intervals in said top 9, while the inner member 5 of the retainer is 100 in the straight form, as shown in Fig. 3, so that when the retainer is bent into hoop form the successive sections of the top 9 intervening between the slits or incisions 12 can spread apart to the extent necessitated by the 10 difference in the diameters of the inner and outer portions of said top 9.

The flange 6 and the interlocked flanges

10 and 11, which occupy a horizontal position in the retainer, are, while the parts of the retainer are in the straight condition, notched as shown at 13 in Figs. 2, 3 and 4 5 so that when the retainer is bent into hoop form the inner portions of said flanges can contract sufficiently to compensate for the lesser diameter of said edges as compared with the outer edges of the flanges.

10 The hook-like retainer is intended to be applied to the projecting ends of the staves 1 by pressure so that it retains its position partly by reason of the engagement of the bead 7 with the outer wire 3^a of the end pair 15 and partly by reason of its frictional hold upon the ends of the staves. The retainer also serves to bring the ends of the staves into proper registry with one another and thus perfects the symmetry of the end of the 20 barrel while at the same time it armors the ends of the staves and protects them from injury which might otherwise be caused by rough handling of the barrel, the four thicknesses of metal at the outer corner of the retainer rendering this part of the same extremely rigid and well calculated to resist the blows upon it caused when the barrel is 25 dropped endwise upon the ground or upon a floor or platform, or when the barrel is 30 being rolled while supported upon the ends of the staves.

I claim:

1. The combination of a barrel composed of staves interwoven with pairs of wires, a 35 head resting upon the inner wire of the end pair, and a retainer of inverted U-shape in cross section, said retainer being passed over the ends of the staves and the inner member of the retainer having an inwardly projecting flange overlapping the peripheral portion of the barrel head so as to maintain said head upon its seat on the inner wire, the outer member of the retainer having thereon a hollow bead for engaging the outer 40 wire of the end pair, and said outer member of the retainer having beyond said hollow bead a flaring flange for facilitating the engagement of said outer member of the retainer with said outer wire.
- 45 2. A barrel head retainer consisting of inner and outer members one lying against the inner faces of the staves and the other against the outer faces of the same, the inner member having an inwardly projecting flange for engaging the barrel head and said 50 members being united by interlocked flanges at the outer corner of the retainer and being

retained in rigid relation to one another by reason of said interlocked flanges.

3. A barrel head retainer consisting of 60 inner and outer members one lying against the inner faces of the staves and the other against the outer faces of the same, the inner member having an inwardly projecting flange for engaging the barrel head and said 65 members being united by interlocked flanges located at the outer corner of the retainer and bent down upon the top of the same and being retained in rigid relation to one another by reason of said interlocked flanges. 70

4. A barrel head retainer consisting of inner and outer members one lying against the inner faces of the staves and the other against the outer faces of the same, the inner member having an inwardly projecting 75 flange for engaging the barrel head, said members being united by interlocked flanges at the outer corner of the retainer, and being retained in rigid relation to one another by reason of said interlocked flanges, and the 80 outer member of the retainer having a hollow bead formed thereon for engaging a wire which constitutes part of the barrel structure.

5. A barrel head retainer consisting of inner and outer members one lying against the inner faces of the staves and the other against the outer faces of the same, the inner member having an inwardly projecting 85 flange for engaging the barrel head, said 90 members being united by interlocked flanges located at the outer corner of the retainer and bent down upon the top of the same, and being retained in rigid relation to one another by reason of said interlocked flanges, 95 and the outer member of the retainer having a hollow bead formed thereon for engaging a wire which constitutes part of the barrel structure. 100

6. A hoop-shaped retainer for barrel heads, said retainer being U-shaped in cross section and comprising two members united at the outer corner of the retainer by an interlocked horizontal joint, the component parts of which joint are notched so as to 105 facilitate the bending of the retainer into hoop form.

In testimony whereof, I have signed my name to this specification, in the presence of two subscribing witnesses.

EDWARD W. ROBINSON.
